US0D1112142S

(12) **United States Design Patent** (10) **Patent No.:** **US D1,112,142 S**
(45) **Date of Patent:** **** Feb. 10, 2026**

(54) **DISPLAY DEVICE**

(71) Applicant: **Samsung Display Co., LTD.**, Yongin-si (KR)

(72) Inventors: **Myeong Il Choi**, Yongin-si (KR); **Seonwoo Pyo**, Yongin-si (KR); **Juyeon Baek**, Yongin-si (KR); **Woo Won Lee**, Yongin-si (KR)

(73) Assignee: **Samsung Display Co., Ltd.**, Yongin-si (KR)

(**) Term: **15 Years**

(21) Appl. No.: **29/935,966**

(22) Filed: **Apr. 4, 2024**

(30) **Foreign Application Priority Data**

Oct. 6, 2023 (KR) 30-2023-0039231

(51) **LOC (15) Cl.** **14-02**

(52) **U.S. Cl.**

USPC ..... **D14/341**; D14/138 AB

(57) **CLAIM**

The ornamental design for a display device, as shown and described.

DESCRIPTION

FIG. 1 is a perspective view of the display device in a folded state according to the present design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof;

FIG. 8 is a perspective view of the display device in an unfolded state according to the present design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines indicate unclaimed portions of the article that form no part of the claimed design.

1 Claim, 14 Drawing Sheets
